ATTORNEY

UNITED STATES PATENT OFFICE.

WILLIAM DICER, OF MARENGO, MICHIGAN.

LAUNDRY-TABLE.

SPECIFICATION forming part of Letters Patent No. 245,144, dated August 2, 1881.

Application filed March 31, 1881. (No model.)

To all whom it may concern:

Be it known that I, WILLIAM DICER, of the town of Marengo, county of Calhoun, State of Michigan, have invented certain new and useful Improvements in Laundry-Tables, of which the following is a specification.

My invention relates to an improved clamp for securing the table to its end support, to securing the bosom-board for small clothes to the large table, and to an improved arrangement of the small tablet.

The object of my invention is, first, to give greater steadiness to the table; second, to provide a more convenient and effective means of fastening small clothes to the upper tablet or bosom-board; third, to provide a convenient and expeditious way of connecting and disconnecting the two ironing-surfaces. I attain these objects by means of the mechanism illustrated in the accompanying drawings, in which—

Figure 1 is a side elevation, showing the apparatus clamped to an ordinary kitchen-table. Fig. 2 is an end elevation. Fig. 3 is a detail view, to be hereinafter referred to. Fig. 4 is a top view. Fig. 5 is a view of the under side with the leg L closed.

In the drawings, D is the principal ironing-surface. b is an iron rod, having its ends a a screw threaded and bent at right angles to the part b, with a hand-nut, d, upon each. These ends a a pass down through the two blocks G G and through the top D, forming hangers for the two levers I I. The short ends i i of levers I I form clamping-jaws, operated by the pins n on the leg L, which is hinged to the table at e. These levers I I are rigid, and united rigidly by means of the broad cross-bar N. The bar b is supported by the blocks G G, and forms a clamping-bridge, as will appear farther on.

Near the inner end, c, of the base-board C is a transverse groove, n, formed to fit and receive the bar b, as shown in Fig. 3. The end c is formed to curve slightly eccentric to the curve of the groove, so that the thickness of C below the groove and bar b is slightly in excess of the thickness of the supports at G G.

Upon the base-board C is fastened an in-

clined jaw, B, and a cleat, E. To this cleat is 50 hinged a small bosom-board, A. This bosom-board is beveled at J to fit the inclined face of jaw B. It also carries a cleat, F, to support it in a horizontal position. On the under side, at the middle point of the outer end, is a knob, o. 55

The operation of the apparatus is as follows: Set it up as shown in Fig. 1, and with the hand-nuts d d bring the short ends i i of the levers I I to a firm bearing on the object to which it is to be secured, and the long ends 60 bearing upon the under side of the pins n on leg L. Now, when leg L is folded forward the ends i i of the levers are released from their hold upon the object to which they are attached. No readjustment of the hand-nuts 65 will be necessary in clamping and unclamping to any object of the same thickness, as the levers will be operated by the folding and unfolding of leg L.

The use of the upper bosom-board, A, may 70 be illustrated by applying it in ironing of a shirt-front, though it is by no means necessarily confined to that garment. Draw the body of the garment over the bosom-board A, bringing the neckband around under the pin or knob o, 75 stretch the garment down, raise the bosom-board to the position shown by the dotted lines, draw the shirt-body down between the beveled end J and jaw B, stretching the shirt-front smoothly upon the bosom-board A. Up- 80 on returning the bosom-board to its horizontal position the shirt-front is held securely stretched during the process of polishing. To remove the upper bosom-board, A, raise the base-board C to a vertical position, when it 85 can readily be backed out from its connection with bar b.

By using two levers united rigidly at their long ends by a broad bar, N, and connecting them at two points, a a, I secure a triangular 90 construction and grasp the support T at two widely-separated points, thus giving a firm and rigid support.

I claim as new and desire to secure by Letters Patent—

1. In a laundry-table, the combination, with the board D, of the hinged leg L, provided with the projecting pins n n, the screw-threaded

rods *a a*, having the hand - nuts *d d*, and the clamping-levers *I I*, rigidly connected together at their rear ends by the cross - bar *N*, substantially in the manner as and for the purpose herein shown and described.

2. The combination, with a laundry - table having clamping-levers *I*, of the rod *b*, having screw-threaded ends, hand-nuts, and blocks *G G*, base - board *C*, provided with the inclined

jaw *B* and cleat *E*, and the bosom-board *A*, 10 hinged to said cleat and beveled at its inner end, and provided with the cleat *F*, substantially as herein shown and described.

WILLIAM DICER.
